LOOSE-LEAF FILING APPARATUS

Richard Fitz Power, Hampstead, London, England, assignor to Morland & Impey Limited, Birmingham, England

Application November 2, 1936, Serial No. 108,908
In Great Britain November 6, 1935

14 Claims. (Cl. 129—16)

This invention relates to looseleaf filing apparatus.

In accounting machine methods at present in use loose sheets, generally referred to as ledger sheets, are arranged in trays and for reference are separated by index cards, and because these sheets are normally resting on edge, have to be cut from a relatively stout material. Generally speaking the stoutness of such sheets is as great as possible commensurate with the capacity of the sheets to pass through typewriting machines and, consequently, a tray of sheets is of such weight that operators cannot easily carry them about.

15 To make these index trays portable, they were mounted on trolleys.

Looseleaf ledgers are also employed in present accounting machine methods.

A looseleaf ledger is a book with a binding mechanism which can be released in order to allow sheets to be separated for reference or to remove a sheet from the book or to insert or replace a sheet.

To permit ready reference to the records on 25 a sheet in a book, the binding mechanism of which has been loosened to permit reference, it is necessary to enter all records outside that marginal area of the sheets located within the binding mechanism. Such marginal area of a 30 sheet is accordingly not available for records.

However, because the sheets are in book form and can be laid flat for storage it is not necessary to have such stout sheets as are employed on trays, accordingly a looseleaf book offers a greater capacity for a given weight whilst advantage 35 of portability is obtained.

To reduce the size of the sheets or to use fewer sheets on a tray to make trays more portable would result in a reduced capacity.

40 In order that the contents of a tray may be readily ascertained, it has been proposed to make a cabinet with sliding drawers each of them constituted by a tray, and this has the advantage that the contents are covered when not in use 45 and if the cabinet is made from sheet metal some protection against the effects of fire is provided. An advantage, however, of a cabinet is that the indices for each tray are assembled for ready 50 reference and it is easy to locate the tray containing the data required.

In some constructions the trays are removable for disposal on trolleys, and generally speaking in such constructions the depth of each compartment in the cabinet is such as to accommodate 55

the full height of the sheets in the trays, which sheets rest on their edges.

It has been proposed in patent specification No. 1,330,301, dated February 10, 1920, Henry C. Brown, to construct a cabinet with trays which hinge about the front of the cabinet when drawn forward, tilt downwardly and then become suspended, the sheets being stored flat in the cabinet on the back plate of the tray and stood on edge on the floor of the tray when it is suspended. Such construction including a back plate fixed at right angles to the floor forms no part of the present invention.

The main object of the present invention is to provide an improved filing apparatus in which 15 relatively thin sheets such as ledger sheets may be employed, hence large capacity obtains, and to provide means so that the sheets when not in use can be laid flat in the same way as if they were in a looseleaf book while the advantage of 20 a filing cabinet is retained.

A filing cabinet construction according to the present invention comprises drawers which, when drawn forward from the cabinet to constitute 25 trays, provides in each such tray a rear wall or end plate fixed at an obtuse angle to the floor of the tray on which the sheets are supported so that the tray may be tilted back on the fixed plate to store the sheets in the cabinet in flat 30 condition, and a front end plate adjustable so as to be set at an obtuse angle to the floor whereby the required working-V may be obtained. The invention comprises also the tray itself having the fixed obtuse end plate at one end and the adjustable end plate at the other end. 35

It may here be explained that in referring to the sheets such as ledger sheets in filing systems of the kind referred to, after the sheet to which reference is required has been found, the sheets are separated and are then set at an inclination 40 to one another and to the vertical. The operator then separates the edges of the sheets on which the sheets are rested so that in side elevation an inverted truncated triangle obtains constituted by the edges of the sheets which are 45 separated and the line, on the floor of the tray, equal to the space between the bottom edges of the sheets. This inverted truncated triangle is termed in the art a "working V" and is to be 50 distinguished from an ordinary V such as would obtain when the pages of a book having a fixed binding are opened or the cards of a card index are separated at their upper edges for reference while the bottom edges still touch.

The operator having found the sheet required 55

may then remove the sheet if an entry has to be made. This entry is usually effected by putting the sheet in a typewriter or calculating machine. Typewriters and calculating machines are now being constructed so that the sheet may be inserted in the front of the platen instead of at the back as was before usual.

Constructions according to the invention permit the employment of sheets of regular and thin form so that in using trays or drawers according to the invention the advantage is obtained that the sheets may be "front fed" into a typewriter or calculating machine instead of at the back of the platen, a process of operation which is essential where sheets are cut away in the marginal area to provide lugs interlocking with binding mechanism. Further, as the latter type of sheet must be relatively stout to produce the desired mechanical effect it follows that the thin sheets available in constructions according to the invention provide a much greater capacity for such record holding devices than if the sheets are required to interlock as heretofore mentioned.

A further advantage arising out of constructions according to the invention is that the rolling or curving of sheets resulting from using the sheets in a typewriter is eliminated as the sheets are restored to flat condition by their own weight and attitude when not in use. Moreover, being flat when not used, there is no tendency for the bottom edges to roll or curve as may result when sheets are stored in vertical condition as in the so-called "vertical" file.

In one practical embodiment of the invention the drawer of the cabinet includes a rear plate fixed with regard to the floor of the tray on which the sheets rest and a front plate hinged below the floor on a slide hinge member so that the working V is obtained throughout variations in the capacity of the tray.

The rear plate may be provided with lugs or rollers which co-operate with rails in the cabinet by which the tray, on being pulled out of the cabinet, is tilted and finally suspended from the cabinet with the floor in horizontal disposition.

When removed the tray may, by means of the lugs on the back plate, be suspended from a stand for ready reference, and the stand may be provided with wheels to minimise the effort of moving the tray.

The invention comprises also a filing tray including a fixed end plate at one end, disposed at an obtuse angle to the tray floor so that the tray may be tilted back on to the fixed plate to store the sheets in the tray in flat condition, and a movable end plate at the other end, the movable plate being hinged below the floor for the sheets and comprising an abutment co-operating with the floor to dispose the movable plate to provide the working V in the sheets; an abutment may also be provided in the movable plate to locate the movable end plate inwardly of the tray in substantial parallelism with the fixed plate so that the sheets on the tray lie between the plates as the pages of a book are disposed between its covers when the tray is tilted back on the fixed end plate to store the sheets in the tray in flat condition.

The floor of the tray may overlap a channel which forms a housing for a slide member on which the movable end plate is hinged and for actuating means for the slide to enforce movement of the movable end plate to adjust the capacity of the tray.

The abutment for the movable end plate may

be included in an attachment at the foot of the plate, the attachment being formed to engage against the underside of the floor and the base of the tray on which the end plate is hinged to dispose accurately the end plate in its two limit positions.

In order that the invention may be more clearly understood reference will now be made to the accompanying drawings which show by way of example preferred embodiments thereof.

In the drawings:

Fig. 1 is a pictorial view of a cabinet formed from sheet metal and including drawers in the form of trays according to the present invention;

Fig. 2 is a sectional elevation through the trays taken on the line II—II of Figure 3;

Fig. 3 being a section taken on the line III—III of Fig. 2.

Fig. 4 is an underside plan of the tray when disposed as shown in Fig. 2, and

Fig. 5 is a side elevation of the tray to reduced scale showing the disposition of the parts of the tray when placed back in the cabinet or otherwise disposed to store the sheets in flat condition.

Figs. 6 and 7 show in front and side elevation respectively the end plate used in the construction illustrated in Figs. 1 to 5 with the slide hinged member omitted, and

Fig. 8 is a fragmentary pictorial detail view looking down from inside the end plate, which is indicated in broken lines only, with parts broken away to show more clearly the end plate adjusting mechanism illustrated in Figs. 1 and 2;

Figs. 9 and 10 show in side and front elevation respectively one form of stand which may be used with a tray according to the invention, and

Figs. 11 and 12 show respectively in side elevation and front elevation a modified form of rear wall or end plate for the tray to include a movable inner face intended to dispose the center of gravity of the tray to assure balance when the tray is lightly loaded.

In the drawings like reference numerals designate the same or similar parts.

Referring now to the drawings, the body portion of the cabinet 1 is, in the construction shown, provided with four drawers each of which, when drawn forward from the cabinet, may be used as a tray for ledger sheets.

Each tray includes a rear end plate 2, a base 3 and a floor 4 on which the lower edges of the ledger sheets 5 rest when the tray is operative, and a movable front end plate 6.

When the tray is operative the base 3 and floor 4 are disposed in a horizontal plane as clearly indicated in Figures 1 and 2.

When, however, the tray is a drawer in the cabinet 1 then the rear end plate 2 is horizontal—as clearly shown in Figure 5—and the base 3 is disposed in the drawer opening at the front of the cabinet (see also Fig. 1).

In the construction shown the rear plate 2 is fixed to the base 3 at an obtuse angle and the front plate 6 is hinged on the base 3, that is to say, below the floor 4 on which the sheets are supported.

The cabinet 1 is provided in each drawer space with rails 7, the configuration of which is clearly shown in Figure 5, on which travel rollers 8 are mounted at the top of the rear plate 2.

To draw forward the tray from the cabinet it is merely pulled forward and the rollers 8 run along the rails 7 and because of the configuration

of the rails the rollers 8 rise until they engage stops 9 at the forward end of the rails.

In this drawn forward position the tray is suspended from the rails as indicated in Figure 1 and in this position the tray is in operative condition, the floor 4 is horizontal, the front wall 6 may be rocked forward and the working-V created.

To facilitate disposal of the tray in operative position in the cabinet the base 3 is provided with openings 10 (see Figure 1) by which the tray can be drawn forward from the cabinet.

Although the tray suspended in front of the cabinet is ready for operation by reason of the spacing of the rail stop 9 from the top of the drawer space, the tray may be lifted vertically so as to clear the stops and be carried to a desk or trolley, stand or the like as desired.

To permit this removal of the tray from the cabinet side walls 11 may be provided with openings 12, thereby providing handles on the side walls 11 by which the tray may be easily carried.

The sheets 5 being always in a flat condition as illustrated in Figure 5, when not in use are very much thinner than the usual ledger sheet employed in a tray, these thin sheets being grouped between index plates 13 only one of which is shown for the sake of clearness, and which, whether in the operative or flat condition of the sheets, holds the latter so that the lower edges are not crumpled or otherwise detrimentally affected, having in mind that it is required to pass these sheets into a typewriter and quite generally to introduce the sheets into the typewriter by feeding the sheet by its lower edge in front of the platen.

To assist in keeping the sheets together, particularly when the tray is thrown back into the cabinet, the surface of the plates 13 may be serrated or roughened to provide a frictional surface tending to hold the juxtaposed sheet to the index plate.

Conveniently the index plates may be formed from aluminium and their surface roughened by sand blasting.

As most clearly shown in Figures 3 and 8, the floor 4 of the tray at its middle part overlaps and is connected to the walls of a channel 14 fixed on the base 3 of the tray. This channel 14 forms a housing for a sliding member 15 (see also Figure 2) carrying a hinge pin 16 for the front plate 6 and a threaded bushing 17 for a threaded spindle 18 having an operating knob 19.

The spindle 18 is secured in a bracket 20 at the back of the tray by a nut member 20a constructed to prevent axial displacement so that rotation of the member 18 causes longitudinal displacement of the sliding member 15 and a consequential lateral displacement of the hinge pin 16 and the front plate 6.

On the front plate 6 and at the foot thereof is fixed an attachment 21 provided with triangular wings 22, set at right angles to the front plate, the upper edges of the wings being flanged over as indicated at 23 (see particularly Figures 3 and 8).

The upper flanges 23 (see Figure 2) of the wings are so formed that when the flanges 23 engage under that part of the floor which overlaps the channel (see Figure 3) the front plate 6 is set to obtain the working-V while the edges 24 of the wings are formed so that when the edges 24 lie on the base of the channel 14, the front plate 6 is substantially parallel with the fixed rear plate 2.

It will be observed that in such a construction

the wings 22 locate the front plate 6 in its two limit positions regardless of whatever adjustment of the front plate 6 has been effected by operating the knob 19 to vary the capacity of the tray.

As most clearly shown in Figures 3 and 8 the floor 4 of the tray includes depressions 25 on which ride lugs 26 formed at the lower edge of the front plate 6. Similar lugs 13a are also provided on the index plates 13, which latter also include lugs 27 (see Figures 2 and 3) which depend into the channel 14 and are apertured in order to be threaded over a rod 28 secured just below the floor of the tray and which passes also through the attachment 21 of the front plate 6.

It will be noted that the lower edges of the index plates 13 and of the front plate 6, are, by the lugs 13a and 26 respectively, raised from the floor of the tray.

The base 3 of the tray may include depressions 29 (see particularly Figs. 1 and 3) for the reception of labels or other indicating means.

From the foregoing it will be understood that when an operator has drawn forward the tray and disposed it in suspended position in front of the cabinet or has withdrawn the drawer and placed it on a desk or table for reference he then merely has to swing forward the front plate 6 on its hinge pin 16 in order to create the desired working-V. The operator will then open the file at the desired index plate 13 and will move the plate 13 and the sheets in front of the plate, that is towards the operator, up to the end plate 6, thereby producing the working-V between the index plate and the sheets 5 immediately to the rear of it which are the sheets to which the operator wishes to refer. In this operation the lugs 13a on the index plates will move along the depressions 25, the lower edges proper of the plates 13 being clear of the floor 4, and the index plates will turn about their points of support in the depressions 25, that is to say, the index plates will hinge below the floor 4 whatever their position thereon and accordingly assist when being turned to push the ledger sheets 5 between them and thereby open the file.

In order to assure this pivoting or hinging of the index plates below the floor surface 4, that is, below the plane containing the lower edges of the sheets in the file, the depressions 25 may be provided with strips of serrated or roughened fabric or metal. For instance, the strips may be made of that fabric material termed "corduroy", in which case the fabric would be so arranged that the ribs of the material lie parallelly with the edges of the sheet to form a series of teeth between which the lugs 13a of the index plates may be lodged to prevent them slipping in a turning movement.

Alternatively, as indicated in Figures 3 and 8, the depressions 25 may carry a corrugated metal strip 30 which will operate similarly as the fabric material just referred to.

Where abutments or teeth are provided in the depressions 25 the operator may have to lift the index plates clear of the ridges in the material in order to move these plates 13 and interposed sheets towards the end plate 6 when this has been pulled open. To this end the apertures in the plates 13 and in the attachment 21 of the front plate 6 are of elongated form to permit this vertical displacement relatively to the securing or anchoring rod 28.

When the operator has finished with the file he merely pushes forward the front plate 6, thereby

closing up the file, and then returns the file into the cabinet in horizontal position.

It has heretofore been stated that the plates 13 may be roughened to prevent the sheets moving out of the file when it is pushed back into the cabinet and it will be noted that as the plates 13 are anchored to the rod 28 their roughened surface tends to prevent the sheets slipping from the file due to the effort exerted in returning the tray 10 into the cabinet while at the same time the weight of the index plates 13 acts as an ancillary means preventing the slipping movement.

When the tray is returned the sheets are flat and should there have been any curling or rolling 18 resulting from the use of the sheets this defect in the sheets will be removed while they lie compressed in a flat condition.

In using looseleaf books and such files it is common practice to insert between the sheets in voices and equivalent documents and this process is known as "stuffing". In books the binding has a tendency to force the stuffed documents out. Constructions according to the present invention allow of a greater amount of stuffing to be effected 25 without the possibility of the inserted documents being ejected from the file.

It is believed that from the foregoing description the nature, operation and general construction of a tray or cabinet and trays according to 30 the invention will be well understood, and reference will now be made to certain details of construction, which, of course, may be varied without departing from the invention.

As already mentioned the front plate 6 may be 35 of sheet metal and it may be reinforced along its vertical and upper edge by beading 31 as most clearly shown in Figures 6 and 7, the front plate being also provided with a depending central lug 6a, including at the foot curl 6b which form 40 bearings in the plate 6 for the hinge pin 16 carried by the sliding member 15, the lug 6a being cut away at the top so that clearance is thereby provided for that part of the floor 4 which overlaps the channel 14.

The attachment 21 is connected, for example by 45 riveting or spot welding, to the plate 6 and as clearly shown in Figure 8, its lower part, depending from the plate 6, taking a similar form to the lug 6a of the plate and then extending downwardly as clearly shown in Figure 2.

The sliding member 15 is preferably of a composite nature including two L-shaped plates, spot welded together and formed to embrace and mesh with the threads on the rod 18, the feet of these 55 two plates being covered by a bifurcated plate 15a, which is secured, for instance by spot welding to the feet of the L-shaped members and includes at one end a curl 15b which forms the bearing for the middle portion of the pin 16 (Figs. 2 60 and 3) that is disposed between the bearings 6b of the end plate 6, thereby in a simple and effective manner the plate 6 is hinged to the sliding member 15.

The construction of the tray may take the 65 form most clearly shown in Figures 2, 3 and 8, that is to say the bottom 3 of the tray may be made from sheet metal providing side spacing ribs 3a, this sheet metal member being spot welded to a sheet metal member comprising the 70 floor 4 and the sides 11 of the tray, in which latter the openings 12 (see Figure 5) are formed.

It may here be noted that in forming the floor member 4, the doubled over portion which provides the overlap to the channel 14 does not extend to the rear of the tray, the length of the over-

lap being clearly shown in Figure 2. The space between the end of the overlap and the rear plate of the tray at the top of the channel 14 permits the assembly of the end plate by the slide 15 and of the adjusting mechanism for 5 the front plate 6.

A reinforcing member 32, see Figures 2 and 3, may run from the front of the floor 4 up to the top of the back plate 2. The back plate 2 may be integral with the member 3 and reinforced 10 at the back by track bars 33, these bars running over rollers 34 mounted on rods 35 disposed at the front of the cabinet, see Fig. 1, so as to facilitate movement of the tray. As indicated in Figures 1 and 5, the rollers 34 and their rods 35 15 may be duplicated and connected by a narrow shelf 36 which localizes the rollers and which acts as a partition which with the bottom plates 3 of the several trays closes up the front of the cabinet when the trays are all returned therein. 20

Although the particular embodiment described refers to the employment of a tray as a drawer in a cabinet the invention covers the form of the construction of the tray itself, as in some cases a cabinet need not be used, for example, 25 the trays could be kept on shelves in a strong room and merely brought from the strong room when required.

One form of the stand construction is shown 30 in Figures 9 and 10. The stand comprises a back 37 and a foot 38 as indicated in the drawings. These members may be made in one piece from steel tubing, the ends of the tubing being connected by a cross member 39 provided with 35 terminal hooks or ears 40.

As clearly shown in Figure 9 the tray is disposed on the stand so that the rollers 8 of the tray (or equivalent lateral lugs may be provided on the tray) rest behind and on the hooks 40, the rear plate 2 of the tray resting against 40 the back 37 of the stand.

The arrangement is such that the center of gravity of the tray and sheets is disposed above the foot 38 so that stable equilibrium exists. Clearly, the tray might be supported on wall 45 brackets provided with horizontal member such as 39 including ears 40 and a support for the rear plate 2 of the tray so that the tray could be suspended from a wall or such form of support might be comprised in a swivelling bracket formed at the side of the desk or table or at the side of the usual form of frame employed for adding and calculating machines, as the sheets may be removed from the tray and put into the platen of a calculating machine in order to make entries 50 on the sheet.

Although the stand construction shown in Figures 9 and 10 is such as could be skidded over a flat surface, this is by way of example only, as rollers or wheels may be provided on a foot such 60 as 38 so as to provide means for carrying the tray from a cabinet or from a strong room over varying floor surfaces to the operator.

The cabinet itself may be made from sheet metal and the front portion of the base 3 of 65 the tray may be inclined upwardly as indicated at 3b, Figure 2, so as to lie flush with the front of the cabinet, as clearly illustrated in Figs. 1 and 5.

It will be noted also with reference to Figures 70 1 and 2 that immediately above the portion 3b the sheet metal is turned inwardly as indicated at 3c to overlie the reinforcement member 32 and that the portion 3c is recessed to form a housing for the operating knob 19. 75

In the modification illustrated in Figures 11 and 12 the back 2 of the tray is provided with a movable face 41 which may be in the form of a plate connected by links 42 and 43 to the rear plate 2, the links being slideable up and down on the rear face of the plate 2. When the tray is full the face plate 41 may be folded back on to the rear plate 2 but when the tray is only, say, half full this face plate 41 may be rocked down on to the floor 4 of the tray, and there forms a rear support for the sheets and index plates in the file in such position that stable equilibrium obtains.

As clearly indicated in Figure 12, the plate 41 may be provided with lugs 44 which enter the depressions 25 in the floor 4 and may be supported in this extended position by the serrations on the strip material 30 if provided in those depressions.

The unit including the floor 4 may include depressions such as 25, beforementioned, preferably furnished with corrugated strips in order to cause the index plates to turn on a hinge line below the floor surface. Where the depressions 25 are not provided in the floor 4 the floor 4 may be provided with strip-like serrated surfaces or strips otherwise roughened, to hinder slipping of sheets or index plates after they have been turned to open the file.

Various refinements may also be incorporated in the cabinet itself, for example, the trackway comprising the rails 7 along which the rollers 8 run when a tray is being moved may also include an upper flange to provide a channel for the rollers 8. Referring more particularly to Figure 5 of the drawings it will be observed that the rail 7 is divided into three zones, each of which fulfils a distinct function with respect to the tray, i. e. the rail 7 may be looked upon as consisting of a supporting portion a, a controlling portion b, and a constraining portion c.

In order to minimise noise during movement of the trays the rollers 34 may be padded or may be made of fibre.

It will be appreciated that other refinements may be incorporated in the tray, for example the front plate 6 may be modified in various ways, for example, if desired the said end plate lugs 26 may be dispensed with, the wire reinforcement or beading being extended along the bottom of the said plate and in order to facilitate the construction of the end plates the metal thereof may not be rolled over around the beading 31 at the corners of the said end plates. Further, the attachment 21 which is secured to the front plate 6 instead of being of substantially rectangular formation may be extended upwardly in V or "heart" formation in order to afford greater strength to the said front plate 6, and if desired the attachment may be reinforced by beading or the like similar to beading 31.

In using looseleaf books and such files it is common practice to insert between the sheets invoices and equivalent documents and this process is known as "stuffing". In books the binding has a tendency to force the stuffed documents out. Constructions according to the present invention allow of a greater amount of stuffing to be effected without the possibility of the inserted documents being ejected from the file.

What I claim is:

1. A filing cabinet comprising drawers which, when drawn forward from the cabinet to constitute trays, provides in each such tray a rear wall or end plate fixed at an obtuse angle to the

floor of the tray on which the sheets are supported so that the tray may be tilted back on the fixed plate to store sheets in the tray in flat condition, and a front end plate adjustable so as to be set at an obtuse angle to the floor whereby the required working V may be obtained. 5

2. A filing cabinet comprising drawers which, when drawn forward from the cabinet to constitute trays, provides in each such tray a rear wall or end plate fixed at an obtuse angle to the floor 10 of the tray on which the sheets are supported, and a front end plate adjustable so as to be set at an obtuse angle to the floor said front plate being hinged below the floor on a slideable hinge member so that the working V is obtained throughout variations in the capacity of the tray. 15

3. A filing tray comprising a fixed end plate at one end of the tray disposed at an obtuse angle to the tray floor so that the tray may be tilted back onto the fixed plate to store the sheets in the tray in flat condition and a front end plate hinged below the floor on a slideable hinge member and comprising an abutment co-operating with the floor to limit pivoting of the plate to provide the working V in the sheets. 20 25

4. A filing tray including a fixed end plate at one end, disposed at an obtuse angle to the tray floor so that the tray may be tilted back on the fixed plate to store sheets in the tray in flat condition, and a movable end plate at the other end, 30 the movable plate being hinged below the floor for the sheets and comprising an abutment co-operating with the floor to limit pivoting of the movable plate to provide the working V in the sheets.

5. A filing tray including a fixed end plate at one end, disposed at an obtuse angle to the tray floor so that the tray may be tilted back on the fixed plate to store sheets in the tray in flat condition, a movable end plate at the other end, the movable plate being hinged below the floor for the 40 sheets and comprising an abutment co-operating with the floor to limit pivoting of the movable plate to provide the working V in the sheets, and an abutment to locate the movable end plate inwardly of the tray in substantial parallelism with 45 the fixed plate so that the sheets on the tray lie between the plates as the pages of a book are disposed between its covers.

6. A filing tray including a fixed end plate at one end, disposed at an obtuse angle to the tray 50 floor so that the tray may be tilted back on the fixed plate to store sheets in the tray in flat condition, a movable end plate at the other end, the movable plate being hinged below the floor for the sheets and comprising an abutment co-operating with the floor to limit pivoting of the movable plate to provide the working V in the sheets, and wherein the floor of the tray overlaps a channel which forms a housing for a slideable member on which the movable end plate is hinged 60 and for actuating means for the slide to enforce movement of the movable end plate to adjust the capacity of the tray. 55

7. A filing tray including a fixed end plate at one end, disposed at an obtuse angle to the tray 65 floor so that the tray may be tilted back on the fixed plate to store sheets in the tray in flat condition, a movable end plate at the other end, the movable plate being hinged below the floor for the sheets and comprising an abutment co-operating with the floor to limit pivoting of the movable plate to provide the working V in the sheets, and wherein the floor of the tray overlaps a channel which forms a housing for a slideable member on which the movable end plate is 70 75

hinged and for actuating means for the slide to enforce movement of the movable end plate to adjust the capacity of the tray, said abutment comprising at the foot triangular wings set at right angles to the movable plate formed to engage the overlap of the channel by the upper edges of the wings thereby setting the plate in open position, said movable plate being hingedly connected to a slide member movable along the base of the tray.

8. A filing tray including a fixed end plate at one end, disposed at an obtuse angle to the tray floor so that the tray may be tilted back on the fixed plate to store sheets in the tray in flat condition, a movable end plate at the other end, the movable plate being hinged below the floor for the sheets and comprising an abutment co-operating with the floor to limit pivoting of the movable plate to provide the working V in the sheets, and wherein the floor of the tray overlaps a channel which forms a housing for a slideable member on which the movable end plate is hinged and for actuating means for the slide to enforce movement of the movable end plate to adjust the capacity of the tray said abutment comprising triangular wings set at right angles to the movable plate formed to engage the overlap of the channel by the upper edges of the wings and the base of the tray by the lower edges of the wings thereby setting the plate in open and closed position, said movable plate being hingedly connected to a slide member movable along the base of the tray.

9. A filing tray according to claim 8 wherein the abutment for the movable end plate is included in an attachment at the foot of the plate, the attachment being formed to engage against the underside of the floor and the base of the tray on which the end plate is hinged to limit pivoting of the end plate accurately in the two directions of movement.

10. A filing tray according to claim 4 wherein index plates are anchored to the tray by a rod threaded through them and the plates are roughened to assist in holding the sheets in the tray when turned on to the rear plate with the sheets flat.

11. A filing tray according to claim 4 wherein the floor of the tray is formed with channels and the tray is provided with a plurality of index

plates each comprising lugs depending into the channels to provide pivots for the plates below the floor of the tray to assist in producing the working V when the tray is moved into open position the lower edges of said plates being disposed above said floor.

12. A filing tray according to claim 8 wherein the floor of the tray is formed with channels and the tray is provided with a plurality of index plates each comprising lugs depending into the channels to provide pivots for the plates below the floor of the tray to assist in producing the working V when the tray is moved into open position the lower edges of said plates being disposed above said floor and wherein the index plates are anchored to the tray by a rod threaded through them and the plates are roughened to assist in holding the sheets in the tray when turned on to the rear plate with the sheets flat.

13. A filing tray according to claim 4 wherein the floor of the tray is formed with channels and the tray is provided with a plurality of index plates each comprising lugs depending into the channels to provide pivots for the plates below the floor of the tray to assist in producing the working V when the tray is moved into open position the lower edges of said plates being disposed above said floor and a rack device arranged in the channels for the index plates to co-operate with the lugs on the index plates in order to prevent slipping thereof when the said index plates are being pivoted.

14. A filing tray according to claim 8 wherein the floor of the tray is formed with channels and the tray is provided with a plurality of index plates each comprising lugs depending into the channels to provide pivots for the plates below the floor of the tray to assist in producing the working V when the tray is moved into open position the lower edges of said plates being disposed above said floor, and wherein the index plates are anchored to the tray by a rod threaded through them and the plates are roughened to assist in holding the sheets in the tray when turned on to the rear plate with the sheets flat and a rack device arranged in the channels for the index plates to co-operate with lugs on the index plates in order to prevent slipping thereof when the said index plates are being pivoted.
